UNITED STATES PATENT OFFICE

BERT VANDERWILT, OF EVERETT, WASHINGTON

DUST COLLECTING BAG FOR VACUUM SWEEPERS

Application filed October 1, 1929. Serial No. 396,515.

My invention relates to improvements in dust collecting bags for vacuum sweepers, and it consists in the combinations, constructions and arrangements hereinafter described and claimed.

The purpose of this invention is to eliminate the objectionable and filthy feature of cleaning the dirt and solids from the bag which is used to collect the dirt in devices such as vacuum cleaners, cleaners, sanding machines, planers, saws, stone polishers, etc. The dirt and solids are collected in a separate collecting bag which is removable and which may be thrown away, thus obviating the shaking of the main dust bag which is now the practice. A new bag replaces the one thrown away.

I provide novel means for permitting the full bag to be tied into a package upon removal from the large bag, whereupon it may be burned or otherwise disposed of.

A further object of my invention is to provide a device of the type described which is extremely simple in construction and which is durable and efficient for the purpose intended.

Other objects and advantages will appear as the specification proceeds, and the novel features will be particularly pointed out in the claims hereto attached.

My invention is illustrated in the accompanying drawings, in which:

Figure 1 is a perspective view of a vacuum cleaner employing my invention,

Figure 2 is a section along the line 2-2 of Figure 1,

Figure 3 is a section along the line 3-3 of Figure 2, and

Figure 4 is a perspective view of one of the refuse bags.

In carrying out my invention, I make use of a vacuum sweeper indicated generally at 1. A dirt conveying conduit 2 leads from the sweeper 1 and enters a main bag 3. In Figure 3 I show the conduit or tube 2 as having a collapsible end 4. This end closes the upper end of the tube 2 when the sweeper stops functioning. This prevents the dirt and solids from falling back into the tube 50 and being conveyed back into the blower in

the machine when the dirt is shaken down in the main bag in order to transfer it to a refuse bag 5.

The refuse bag 5 is secured to an outlet 6 of a conical-shaped partition 7 by strings 8 or other suitable fastening means. The partition 7 conveys dirt and solids from the main bag 3 into the refuse bag 5. These solids, of course, have previously been delivered to the main bag 3 by means of the tube 2. The neck of the refuse bag is held open by a fiber collar 9 disposed in the outlet 6.

It will be seen from Figure 1 that the lower portion of the main bag 3 may be opened in order to gain access to the refuse or collecting bag 5. I have shown a zipper 10 for closing and opening the portion of the main bag disposed adjacent to the refuse bag 5.

From the foregoing description of the various parts of the device, the operation thereof may be readily understood.

A collecting bag 5 is secured to the outlet 6 by the string 8, and the device is ready for use. A good part of the dirt collected in the main bag 3 will drop into the refuse bag 5.

In removing the bag 5, the operator opens the lower portion of the main bag 3 by means of the zipper 10 and then shakes the main bag 3 for causing all of the dirt to enter the refuse bag. The string 8 may now be untied in order to remove the refuse bag and then the opening in the bag can be tied shut by means of the same string if desired, as shown in Figure 4.

A new collecting bag 5 is secured to the outlet 6 by strings 8, and the machine is ready for further use. It will be seen that the shaking of the bag in the open air is obviated, and there is no muss in handling the refuse bag 5 because it is made of a non-porous material. The device is extremely simple in construction, and can be adapted to uses other than for vacuum sweepers.

Although I have shown and described one embodiment of my invention, it is to be understood that the same is susceptible of various changes, and I reserve the right to employ such changes as may come within the scope of the invention as claimed.

I claim:

1. In combination, a dust collecting bag, a conical-shaped partition disposed in said bag, a non-porous refuse bag removably secured to the open end of the partition for receiving dirt from the main bag, a conduit for delivering dirt to the main bag at a point above the partition, said conduit having a flexible end portion extending above the partition, and means for opening the main bag below the partition for gaining access to the non-porous bag.

2. In combination, a dust collecting bag, a conical-shaped partition disposed in said bag, a refuse bag removably secured to the open end of the partition for receiving dirt from the main bag, a conduit for delivering dirt to the main bag at a point above the partition, said conduit having a flexible end portion extending above the partition, and means for opening the main bag below the partition for gaining access to the non-porous bag.

3. In combination, a main bag, a partition disposed in the bag, a dirt conveying conduit for conveying material above the partition, and a refuse bag removably secured to the outlet end of the partition, said conduit having a flexible end portion extending above the partition.
